Attorneys

UNITED STATES PATENT OFFICE.

JAMES ARTHUR SPEER, OF ROZEL, KANSAS.

HEADER ATTACHMENT.

Application filed August 24, 1923. Serial No. 659,135.

To all whom it may concern:

Be it known that I, JAMES A. SPEER, a citizen of the United States, residing at Rozel, in the county of Pawnee and State of 5 Kansas, have invented a new and useful Header Attachment, of which the following is a specification.

This invention relates to harvesting machines and more particularly machines commonly known as headers.

The primary object of the invention is to provide means for automatically unclutching the cutter bar and gearing of the header while the machine is being turned in one 15 direction.

Another important object of the invention is to provide means for conveying the material laterally after the same has been cut by the machine.

20 A still further object of the invention is to provide means for manually controlling the clutch members of the machine to permit the endless conveyors to be readily and easily thrown into and out of operation.

25 With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

35 Referring to the drawings:

Figure 1 is a side elevational view of a header constructed in accordance with the invention.

Figure 2 is a fragmental plan view 40 thereof.

Figure 3 is a sectional view taken on line 3-3 of Figure 2.

Figure 4 is a sectional view taken on line 4-4 of Figure 2.

45 Figure 5 is a sectional view taken on line 5-5 of Figure 1.

Figure 6 is a longitudinal sectional view through the lateral adjustable conveyor.

Referring to the drawings in detail, the 50 frame of the machine is substantially triangular and comprises a relatively long rod

5, an axle section 6 to which the rod 5 is secured, and an angularly disposed rod 7 which is also secured to the axle 6, through the coupling 8.

The rod 5 has connection with the axle 6 through the coupling 9, which couplings 8 and 9 are of constructions to embrace portions of the axle to allow the axle to move therein. These couplings 9 provide bearing members 10 that have rearwardly extending lugs 11 to which the arms 12 that support the cutter bar are pivotally secured, whereby the arms 12 may be moved vertically to adjust the cutter bar with respect to the 65 ground surface.

Supported by the axle 6 and secured thereto adjacent to the outer end thereof, are forwardly extended arms 13 that have connection with the cutter bar supporting frame at 70 the other side thereof to assist the arms 12 in supporting the weight of the cutter bar and the frame.

The cutter bar frame includes a trough-like member 14 that has openings formed in the side bars thereof to receive the shafts 15 on which the rollers 16 are mounted, which rollers provide supports for the endless conveyor 17. Pivotally mounted on the rod 5 are the supporting arms 18 to which are secured the rods 19 that extend rearwardly and have their adjacent ends connected by means of the latch member 20 that carries a movable member 21 adapted to move in the openings 22 of the adjusting bar 23 that is supported at the rear of the machine.

These arms 18 also have connection with the rods 24 and 25 that connect with the upwardly extending arms 26 carried by the bearings 10, which arms also have connection with the arms 12 through the rods 27. Thus it will be seen that upon movement of the rods 19, the arms 18 and rods connected therewith will be moved to adjust the cutter bar supporting frame vertically.

95 Forming a part of the frame of the machine is an auxiliary frame including a rearwardly extending bar 28 which has its rear end connected to the main frame of the machine by means of the bar 29. The bar 29 100 supports bearings 30 and 31 in which the shaft 32 operates, the shaft 32 carrying a

pinion 33 at one end, and a sprocket 34 at the opposite end, the sprocket being designed to receive motion from the sprocket 35 through the chain 36 operating over the 5 sprockets.

The sprocket 35 is secured to the wheel 37 so that movement of the wheel 37 will produce a relative movement of the sprocket 35 and chain 36 and sprocket 34. In order 10 that the sprocket 34 may be clutched to the shaft 32 to operate the shaft 32 a clutch member 38 is provided and splined on the shaft 32, suitable means such as a lever 39 being provided for moving the clutch member 38 to its inactive position, the coiled spring 40 being provided to normally urge the clutch face 38 into engagement with the clutch face 41 formed on the hub of the sprocket 34.

20 Meshing with the beveled pinion 33 is a beveled pinion 42 carried on one end of the shaft 43 that is mounted in bearing 44 and bearing 45 in the arm 46. A roller operating shaft is indicated at 47 and has connection 25 with the shaft 43 through the universal connection 48, the opposite end of the shaft being connected with a roller 49 at 50, over which roller the laterally disposed endless conveyor 17 operates.

30 Secured to the rod 5 is a bearing 52 in which the shaft 53 is journaled, the bar 28 also supporting bearing member 54 in which the outer end of the shaft 53 operates. A clutch member 55 is also mounted on the shaft 53 and cooperates with the clutch member 56 of the sprocket wheel 57 to lock the sprocket wheel to the shaft 53 and cause rotation of the shaft 53 and pinion 58 supported at the outer end thereof. The 35 clutch member 55 is normally held in its active position through the medium of the spring 59 there being provided a clutch lever 60 in the form of a bell crank lever which is pivotally supported at 61 on the arm 61' to throw the clutch member 55 to its inactive position.

40 A rod 62 has connection with the operating clutch lever 60 and has its forward end connected with one end of the chain 63 operating over the sprocket wheel 64 that is mounted on the shaft 65. This shaft 65 is journaled in a bearing of platform 66 mounted at one end of the rod 5, and as shown, supports the sprocket 64 to which 45 one end of the chain 63 is connected. As the wheel 67 is turned in one direction to guide the machine it is obvious that the shaft 65 will be operated to the end that the clutch member 55 will be automatically released, throwing the shaft 53 out of operation.

50 If it is desired to manually control the clutch mechanism, the pedal 68 is provided, which pedal is pivotally supported on the platform 66 and has connection with the rod

55 69 which in turn is connected with the rod 62 to move and throw the clutch member 55 out of operation. Associated with the shaft 53 is a shaft 70 that carries a pinion 71 meshing with the pinion 58 to receive motion therefrom. The shaft 70 also supports the pinion 72 that is in mesh with the pinion 73, mounted on one end of the shaft 74. The shaft 70 has connection with the shaft 75 that in turn operates the outer 70 75 roller 16 to impart rotary motion thereto.

At the front end of the shaft 74 is a universal connection 76 that has connection with the shaft 77 which has connection with the roller 78 over which the endless conveyor 51 operates, which endless conveyor operates over idle rolls 79 at the outer end thereof.

Connected with the arms 18 is a flexible member indicated at 80 that passes through 85 an eye in the upper end of the arm 81, which flexible member has one end thereof connected to the laterally extending conveyor 51 at 82, so that as the rods 19 are moved, the laterally extending conveyor may move therewith, to the end that the discharge end of the laterally extending conveyor may be adjusted vertically.

90 Mounted on the axle 6 is a sprocket 83 over which the chain 84 passes, which chain also moves over the sprocket 85 carried on the shaft 86 of the reel 87, for transmitting rotary movement of the axle 6 to the reel 87. A frame 85' has connection with the 95 axle and carries sprockets 88 to hold the chain 84 taut at all times.

100 In the use of the device, it will be obvious that the device may be positioned adjacent to a suitable receiving wagon, the laterally extending conveyor having its upper end disposed over the wagon to discharge material thereinto.

I claim:—

1. In a harvesting machine, a frame, a cutter bar, a conveyor operating at the rear of the cutter bar, a laterally extended conveyor to receive material from the first mentioned conveyor, shafts for imparting rotary movement to the laterally extended conveyor, shafts operating to transmit rotary motion to the first mentioned shafts, sprockets on the last mentioned shafts, clutch members operating to clutch the sprockets to the shaft, a steering wheel for the frame, and means controlled by the steering wheel and having connection with the clutch members for moving the clutch members to their inactive positions when the steering wheel is turned.

110 115 120 125 130 2. In a harvesting machine, a frame, a laterally disposed endless conveyor supported by the frame, shafts for operating the endless conveyor and having pinions, operating shafts having pinions meshing with the pinions of the first mentioned

shafts, sprockets on the last mentioned shafts, clutch members for clutching the sprockets to their shafts, a clutch lever associated with one of the clutch members, 5 a rod extending from the clutch lever, a steering wheel at the forward end of the frame and having a vertical shaft, a sprocket on the vertical shaft, a chain on the sprocket, said chain having connection with 10 the rod, and said chain adapted to move to

operate the rod to throw out the clutch member when the steering wheel is turned.

In testimony that I claim the foregoing as my own, I have hereto affixed my signature in the presence of two witnesses.

JAMES ARTHUR SPEER.
